UNITED STATES PATENT OFFICE.

WILLIAM C. MORRILL, OF NEW YORK, N. Y.

LIQUID-SOAP DISPENSER.

Application filed June 9, 1919. Serial No. 302,972.

This invention is a dispenser for liquid soap, the same pertaining, more particularly, to devices of that class wherein a containing vessel is fixedly retained in a supporting member, usually a bracket, appropriate means being provided for manual operation to effect the delivery of the liquid material from the bottom portion of said container.

In this class of devices it is usual to employ a container composed of glass and a metal fitting for a dispensing valve, the container being manufactured by the process commonly known as "blowing" the glass. As is well known, blow glass containers vary in dimensions, and this is true particularly in the case of containers an end portion of which is contracted to produce a neck for the attachment of a metal fitting, the problem being to so coordinate the metal fitting and the container as to secure a liquid-tight joint at the bottom of said container and to also insure the proper relationship of the metal fitting to the glass container. Moreover, in the practical operations connected with the production of the container, it is necessary to grind off the end face of the glass at the neck, but experience shows that even with this precaution a considerable variation exists in the end faces of the necks of different containers similar in design and size, and, further, that it seldom happens that the lower end of the container is ground off at a right angle to the axis of said container as should be done.

One part of this invention consists of means whereby the glass container and the metal fitting are mutually adapted to each other in such a manner as to secure a liquid-tight connection between the bottom part of the container and the fitting as well as to compensate for variations in the form and dimensions of the container. To these ends, the container is provided with a neck the lower part of which is formed with an external thread, whereas the fitting is provided with an internal thread so as to enable said parts to be separably coupled by a screw connection. A compressible gasket is positioned at a suitable point intermediate the container and the fitting for the purpose of securing the desired liquid-tight connection, and in a preferred embodiment of the invention the neck portion of the container is provided with a shoulder intermediate the ends of said neck, with which shoulder con-

tacts the gasket, thus enabling me to secure a true and even bearing surface for said gasket in order to compress the latter by screwing the fitting into position, the finish or the physical condition of the glass at the bottom of the neck being immaterial so far as concerns the liquid-tight connection for the reason that said fitting does not contact with the bottom face of the neck, hence it is not required that said bottom face of the neck be ground off at right angles to the axis of the glass container.

Another part of the invention consists in means for precluding the removal of the metal fitting from the container when the latter is mounted in the supporting member, and, further, to provide means whereby the container may be attached to and dismounted from the supporting member without subjecting said container to breakage or fracture during the performance of the mounting or dismounting operations.

To these ends, I construct the neck portion of the container in a manner to produce a plurality of collars one of which is of less diameter than the other so as to permit the ready movement of the valve fitting and container neck through the supporting member. The collar of larger diameter is formed with a male thread adapted to be screwed into a female thread provided within an annular part of the supporting member, whereby the collar at the neck portion of the container may be attached to the supporting member without permitting the glass body to come into contact with the supporting member so that the container can be attached and detached with a minimum risk of fracture.

The metal fitting for the dispensing valve is formed with a tubular member and with an outstanding flange, and in assembling the fitting relatively to the container this tubular member embraces the collar of small diameter on the neck whereas the flange of said fitting is spaced by the interposed gasket with respect to the shoulder intermediate the two said collars of the neck portion. In mounting the container on the supporting member, the threaded collar is screwed into the annular part until the flange of the fitting is in contact with the flange of said annular part, as a result of which the container has a firm bearing in the annular part and the flange of said metal fitting is so

seated upon the flange of the annular part that said fitting or the valve cannot be detached from the container during the period that the container is attached to the supporting member.

In this connection it is desired to state that the lower threaded part of the glass neck is free from contact with the annular supporting member and, further, that the flange of the metal fitting is so seated upon said annular supporting member as to utilize the elasticity of the gasket as a buffer in reducing the stresses upon the glassware when mounted on the bracket.

Another part of my invention consists in the provision of means for locking the container to the supporting member, and the same being effective in all variations in the dimensions of that part of the container with which cooperates said locking means. To these ends, the collar of large diameter is provided with a bevel on its upper face, which bevel is exterior to the collar and positioned well below the surface of the container body. Cooperating with said beveled face is a locking member, preferably embodied in the form of a screw mounted in a part of the supporting member, and in one form this screw is concealed from access when in operative contact with beveled face of the container.

Other features and advantages of the invention will appear from the following description taken in connection with the drawings, wherein—

Fig. 1 is an elevation, with certain parts in vertical section, of a soap dispenser embodying this invention.

Fig. 2 is an elevation of the lower part of the container detached from the bracket and illustrating the formation of the neck thereof.

Fig. 3 is a detail view, partly in section and partly in elevation, of the supporting bracket.

Fig. 4 is a detail view, partly in section and in elevation, of the metal fitting for the dispensing valve.

Fig. 5 is a plan view of the fitting shown in Fig. 4.

The container A is composed, preferably, of glass having a desired shape and dimensions. Said container is preferably closed and flattened at the top, as at a, in order that on dismounting it from the bracket F said container may be turned over and rest upon a table, or other surface, for filling and cleaning it, the flat surface a affording a firm bearing for the container when inverted. Another advantage is that the container is hermetically closed at the top and that it requires no cover for a top opening, thus attaining economy in the manufacture of the container and dispensing with a separate cover, the latter in other styles of con-

tainers being composed of metal adapted to be locked in place and affording an additional item to the cost of manufacture. The bottom part of the container is formed with a neck, indicated generally at B and in effect consisting of two collars b b', whereof the upper collar b is larger in diameter than the lower collar b'. The upper collar extends for an appreciable distance below the body of container A, and the outer surface of this collar at the upper portion thereof is formed to produce an incline or bevel c sloping downwardly and outwardly from that surface of least diameter at the under portion of the container, see Figs. 1 and 2. Said collar b is formed on its annular surface and below the bevel c with an external thread b⁴, see Figs. 1 and 2. Incidental to the use of two collars b b' of different diameters, a shoulder or ledge b² is produced on the neck, see Fig. 2. The smaller collar b' is provided with an external thread d, the same extending preferably from the shoulder b² to the lower edge of the neck B, the under face of which neck may be finished in any desired way.

The neck at the lower part of the container opens downwardly, see Fig. 1, said opening being closed by a metal fitting C containing a dispensing valve E, said fitting being of the kind shown generally in my prior Patent No. 1,235,913, and the said valve being constructed and adapted for operation as disclosed in said prior Patent No. 1,235,913, and in Patent 1,199,913, and reissued Patent 13,898. The fitting is composed preferably of a die casting although a metal stamping may be used. As shown, said fitting comprises a tubular body f, a depending boss f' and a radial flange e at the top edge of the tubular body. The tubular body is open at the top flanged portion e thereof, whereas the boss f' is open for the operation of the valve stem. Said tubular body f is provided with an internal thread g, corresponding to the external thread d of the container neck, whereby the fitting is adapted by a rotative movement to be screwed detachably to the lower collar b' of the container neck B.

The container is composed of glass and is produced in the manner usual in the art by blowing the glass, the container used in my invention being provided with a depending neck characterized by a form of construction which includes the two threaded collars b b' and a shoulder b², the plane of which shoulder is intermediate the threads b⁴, d. It is usual in the production of glass containers with neck portions to true up the end face of the neck by grinding off the glass, said grinding operation being performed with more or less irregularity as a result of which the bottom or end face of the neck may or may not be in a plane at

a right angle to the vertical axis of the container.

D is a gasket composed of compressible material, the same consisting preferably of 5 rubber and the internal diameter of which corresponds substantially to the diameter of the lower threaded collar b' of the neck. Said gasket is fitted around the collar b' and into contact with the shoulder b², the latter 10 acting as a seat for said gasket. The fitting C is screwed upon the collar b' for the upper flanged edge of said fitting to have contact with the gasket, the latter being thus interposed between the fitting and the neck so as 15 to secure a liquid tight joint between the metal fitting and the glass container in order to preclude leakage of the liquid material. The gasket D is of such thickness and the metal fitting is so proportioned relatively to 20 the neck B that when said fitting is screwed upon the neck so as to compress the gasket said fitting does not come into contact with the end face of the neck B, see Fig. 1, whereby any irregularity in the plane of the end 25 face of the glassware will have no effect upon the liquid tight connection between the glassware and the metal fitting, it being noted that the shoulder b² is in a plane substantially at right angles to the axis of the container so as to constitute a true and even bearing surface or seat for the gasket.

When the container is screwed into the bracket, the flange e of the metal fitting is in contact with a flange m of the metal 35 bracket; in other words, there is no direct contact between the shoulder b² of the glassware and the flange m of the bracket, but on the contrary, there is a metal to metal contact due to the engagement of flange e with 40 flange m, the elastic gasket D being intermediate the shoulder b² and the flange m of the metal bracket. In the operation of coupling the glass container to the metal bracket, the container is screwed into the bracket until the flange e of the metal fitting 45 arrests the rotative movement, the gasket D serving as a buffer or cushion between the glassware and the metal bracket.

The container is mounted detachably in a 50 supporting member F, shown in Figs. 1 and 3 as a bracket, the arm f² of which is integral with a face plate i and a ring j, said face plate being attached in a suitable manner to a wall or other surface. The ring 55 is formed with an internal thread k, corresponding to the external thread b⁴ of the neck, and said ring is provided with a flange m, the same being positioned at the bottom edge of the ring and extending inwardly 60 with respect thereto and beyond the plane of the internal thread k. The bracket is provided with an upstanding lug n, for supporting a container locking member herein 65 shown as a screw G, although it is apparent other means may be employed for retaining 70 the container in a locked relation to the bracket. The screw is mounted in a thread provided within the lug n, and in the form shown the screw is adapted to be so positioned that its end portion is concealed by 75 and within the lug, thus precluding unwarranted access to the screw and requiring the use of a suitable key G', see Fig. 1, for the manipulation of the screw in order to unlock and lock the container with reference to the 80 bracket.

Assuming that the container is dismounted from the bracket and that it is desired to charge it with the liquid material, the container is turned over and placed on a table, etc., resting upon the closed flat face a. The metal fitting is now disconnected by a rotative movement in order to unscrew it from the neck B, thus permitting the fitting and the valve to be taken off the container. The liquid material is now introduced through the opening in the neck, after which the gasket D is placed around the collar b' so as to rest against shoulder b², and the fitting 85 and the valve are replaced in order that the fitting may compress the gasket D. The fitting is screwed on the collar in a manner to tightly close the open neck of the container so as to render the latter substantially 90 air and liquid tight. The container is now turned back to a normal position and the neck, fitting and valve inserted into the ring j of the bracket, the container being rotated bodily for its external threads b⁴ to engage 95 the internal threads k of the bracket. The rotation of the container is continued until the flange e of the fitting contacts with flange m of the bracket, the further rotation and downward movement of the container being arrested by flange e occupying the bracket 100 flange m, and the valve and the fitting protruding well below the bracket. The lock screw G is now rotated in the lug n for one 105 end of the screw to have contact with the beveled face c of the container, whereas the other end of the screw is concealed against 110 access within the lug n, the rotation of the screw being performed by aid of key G', or other appropriate tool.

It will be noted that the container has a 115 fixed engagement with the bracket by reason of its threads b⁴ being in direct contact with the threads k and its shoulder b² being in indirect contact with flange m of the bracket, and, further, that it is locked to said bracket 120 by member G, or its equivalent, thus precluding surreptitious removal of the container. Again, the flange e cooperates with the flange m of the bracket in preventing removal of the fitting and the valve from the container when mounted in the bracket; but to remove the container, it is necessary to withdraw screw G from the path of bevel c, and to unscrew the container from the 125 bracket, the fitting C and valve E being 130

withdrawable with said container in order to preclude any escape of liquid material therefrom.

The parts of my new dispensing device 5 may be manufactured economically, one reason therefor being that the glass container having one opening only can be produced at a cost of one-half to two-thirds below the cost of a glass vessel with openings at 10 the respective ends, it being necessary to grind off one end portion only of the container, and no cover being required for the top of the container, so that the cost of one grinding operation and of said cover are 15 saved and, moreover, the container is airtight at the upper end portion thereof. Again, the bracket and the valve are inexpensive in construction, while at the same time these metal parts are substantial, durable and efficient.

Devices of this character are exposed to the accession of dirt and become quickly soiled in use, but in my device the container 20 is readily dismounted from the bracket, thus 25 permitting free access to the bracket for cleaning it and enabling the operator to dismount the valve and the fitting from the container, whereupon the container can 30 easily be cleaned and refilled and the valve can also be easily cleaned to remove any 35 adhering foreign matter tending to clog up the valve, it being apparent that the valve is exposed for repairs, if necessary. Moreover, no very accurate or nicety of adjustment 40 is required between the fitting and the container, or the container and the bracket, but when the container is screwed into, or unscrewed from, the bracket the glass body of the container does not come into contact 45 with the bracket or any part thereof, thus minimizing the liability to breakage on the part of the container when mounting or dismounting it.

Having thus fully described the invention, 50 what I claim as new, and desire to secure by Letters Patent is:

1. In a dispensing device, the combination 55 of a supporting member provided with a threaded collar, a container provided at its lower part with a threaded neck screwed into said collar for the container to extend upwardly therefrom, said container being provided above said threaded neck with an inwardly directed beveled face, and a locking member 60 attached to the supporting member, said locking member being in contact with said beveled face of the container and co-operable with the latter in precluding the removal of said container from the supporting device.

2. In a dispensing device, the combination 65 of a supporting member provided with a threaded collar, a container the lower part of which is reduced in diameter to produce a threaded neck, said neck being screwed

into said threaded collar and said container being provided above said neck with a beveled face inclining inwardly from the neck portion toward the body portion of the container, and a locking member contacting 70 with said beveled face and co-operable with the supporting member and the container for precluding the removal of said container from the supporting member.

3. In a dispensing device, a supporting 75 member, a container threaded to the supporting member, and a valve fitting attached to the container, said valve fitting having direct engagement with said supporting member.

4. In a dispensing device, a supporting member, a container provided with an upper collar and a lower collar, said container having its upper collar threaded into said supporting member, and a valve fitting 85 screwed to the lower collar, said valve fitting having direct engagement with the supporting member.

5. In a dispensing device, a supporting 90 member provided with a flange, a container having an upper male threaded collar and a lower male threaded collar, said upper collar being screwed into the supporting member, and a valve fitting screwed on the lower collar, said valve fitting being in engagement with said flange of the supporting member.

6. A dispensing device embodying a container the neck of which comprises a plurality of collars one of which is threaded, a 100 supporting member into which is screwed said threaded collar for fixedly and detachably mounting said container, and a valve fitting attached to the other collar of said container, said valve fitting cooperating with 105 said supporting member for precluding removal of said fitting while the container is mounted in the supporting member.

7. In a dispensing device, a supporting 110 collar provided at its lower part with an inwardly directed flange, a container mounted in said collar, and a valve fitting attached to said container, said valve fitting provided with an outwardly directed flange, said flanges of the collar and of the valve fitting 115 mutually co-operating for precluding removal of said valve fitting when the container and valve fitting are assembled relatively to the collar.

8. In a dispensing device, a supporting 120 collar, a container provided with contiguous threaded portions of different diameters, one of said threaded portions constituting a neck and the other threaded portion being threaded into said supporting collar, a valve fitting 125 screwed to the threaded neck of the container, and a compressible member interposed between the valve fitting and the container, said valve fitting having direct contact with said supporting member and said 130

compressible member affording a buffer adapted to preclude fracture of the container by contact with the metal parts upon screwing said container into the supporting collar.

5 9. In a dispensing device, a supporting collar, a container provided with contiguous threaded portions of different diameters producing between said threaded portions an intermediate shoulder, one of said threaded 70 portions of said container being screwed into said collar, a valve fitting screwed on the other threaded portion of the container, said valve fitting being seated in direct metallic contact with said supporting collar, and a 75 compressible member contacting with the valve fitting and with the intermediate shoulder to afford a liquid tight joint above the lower extremity of said container and between the valve fitting and the container.

10 10. A dispensing device embodying a container provided with a neck comprising a plurality of collars, one of said collars having a thread, a supporting member into which the threaded collar is screwed, and a 80 25 valve fitting attached to the other collar of said container and having locking engagement with said supporting member for precluding the removal of said valve fitting by said supporting member, said locking being 85 30 by means cooperable with the supporting member and the neck in addition to the threaded engagement of said parts.

11. In a dispensing device, a container provided with a plurality of contiguous threaded portions of different diameters, the smaller of said threaded portions constituting a neck and said threaded portions being discontinuous by the provision of an intermediate shoulder, a supporting collar into 90 40 which is screwed one of the threaded portions of the container, a valve fitting screwed to the other threaded or neck portion of the container, and a compressible member contacting with the intermediate shoulder of the container and confined between said 95 45 valve fitting and the container to afford a liquid tight connection above the lower extremity of the container neck.

12. In a dispensing device, a supporting member, a container provided with a plurality of collars of different diameters, the smaller one of which collars constitutes a neck, said container having a bevel between the larger of said collars and the external 100 55 surface of the body portion of said container, a valve fitting attached to the smaller collar or neck portion of said container, said valve fitting being engageable with the supporting member, and means contacting with said 105 60 bevel for locking the container relatively to the supporting member.

13. In a dispensing device, a supporting member, a container provided with a plurality of collars of different diameters and producing between them an annular shoul-

der, the smaller of said collars constituting a neck portion to the container, a valve fitting engageable with the smaller collar or neck portion of the container, said valve fitting being directly co-operable with the supporting member to preclude the removal of said valve fitting without dismounting the container from the supporting member, the larger of said collars being threaded into the supporting member. 75

14. In a dispensing device, a container the neck portion of which is formed with a bearing face extending substantially at a right angle to the axis of said container, said bearing face being separate from the end face of the neck portion, a fitting attached to said neck portion, said fitting having a face substantially parallel to the bearing face, and a compressible member intermediate said parallel faces of the fitting and said bearing. 80

15. In a dispensing device, a container the neck of which is provided intermediate its ends with a shoulder the plane of which is substantially at a right angle to the axis of 90 95 said container, a fitting the end face of which is substantially parallel with and is opposed to said shoulder, and a compressible member intermediate said parallel faces of the shoulder and the fitting. 95

16. In a dispensing device, a container the neck portion of which is provided intermediate its ends with a shoulder the plane of which is substantially at a right angle to the axis of the container, a valve fitting provided with an end face substantially parallel to the shoulder, said valve fitting being attached to the neck and separated from the end face of said neck by an intermediate free space, and a compressible member interposed 100 105 between the shoulder and the end face of said fitting.

17. In a dispensing device, a container provided with a reduced threaded neck, said container having a shoulder the plane of which is substantially at a right angle to the axis of said container, a valve fitting provided with an end face substantially parallel with and opposed to the shoulder, and said valve fitting being screwed on the neck and free from contact with the end face of said neck and separated therefrom by an intermediate free space, and a gasket between the shoulder and the end face of the valve fitting so as to be compressible between the shoulder and the fitting and produce a light tight connection above the end face of the neck. 110 115 120

18. A dispensing device embodying a container provided with a depending neck portion, the latter being provided intermediate its ends with a bearing face positioned at substantially a right angle to the axis of the container, a valve fitting embracing said neck and provided with a bearing face parallel and adjacent with the bearing face of the 125 130

6
neck, a gasket intermediate the bearing faces, and complementary means on the neck and the fitting for interlocking the parts.

19. A dispensing device embodying a container provided with a neck portion, a valve fitting attached to said neck portion, the opposing faces of the neck and the fitting being in parallel planes, a gasket in contact with said opposing faces, said gasket fitting 10 said neck portion intermediate its ends, and means for locking the fitting on the neck portion so as to secure the desired contact of the gasket with the opposing faces of the neck and the fitting.
- 15 20. A dispensing device embodying a container the neck of which is provided intermediate its ends with a gasket seat, a valve fitting provided with a gasket seat in parallel relation to the similar seat on the neck, a

gasket in contact with said seats, and coupling means for attaching the fitting to the neck so as to provide for such relative movement of the fitting as will attain a desired coincidence in the relation of the gasket seat in the fitting to the gasket seat on the neck. 25

21. In a dispensing device, a container having a depending reduced neck portion, said neck being provided intermediate its ends with a gasket seat the plane of which is substantially at a right angle to the axis of 30 said container and the extreme end portion of said container being ground off in a plane below and substantially parallel to the gasket seat.

In testimony whereof I have hereunto signed my name this 19th day of may, 1919.

WILLIAM C. MORRILL.
